UNITED STATES PATENT OFFICE.

PATRICK J. DUNN, OF HOLLAND, OHIO.

VACUUM STREET-CLEANING MACHINE.

1,356,272.

Specification of Letters Patent. Patented Oct. 19, 1920.

Application filed November 8, 1919. Serial No. 336,561.

To all whom it may concern:

Be it known that I, PATRICK J. DUNN, a citizen of the United States, residing at Holland, in the county of Lucas and State of Ohio, have invented certain new and useful Improvements in Vacuum Street-Cleaning Machines, of which the following is a specification, reference being had to the accompanying drawings.

This invention relates to an improved vacuum street cleaning machine, which has for its object to provide a simple, efficient and durable machine capable, when manufactured, of being produced for a relatively low cost and sold at a reasonable profit.

Another object of the invention consists in the provision of a vacuum cleaning machine particularly adapted for cleaning streets, alleys, sidewalks and the like, and one which has been found practical which includes novel features of construction.

As a further object of the invention, it is the aim to provide a new construction of machine for cleaning various thoroughfares and one which includes a suction pipe having means for creating a suction therein, and having a suction end through which the debris is drawn, there being rotary brushes adjacent the suction end of the suction pipe to aid in forcing the rubbish or refuse through the suction end, whereby it may be drawn into a suitable receptacle, after passing through the suction pipe. Further, deflecting means is employed adjacent the rotary brushes, whereby the refuse may readily enter the suction pipe.

A still further object of the invention is to provide rotary brushes carried by the suction end of the suction tube having their bristles spirally arranged, the spiral being in opposite directions so that the dirt or refuse will be forced toward the center of the suction end so as to easily enter the suction pipe, and also be brushed upon the deflector plate.

Further, it is the aim to provide improved means for mounting the suction pipe on the rear supporting wheels of the machine tiltably, whereby the suction pipe may be tilted so as to throw the gear connections between the suction creating means and the drive axle out of gear. When the suction means is thrown out of gear, the rotary brushes of the suction end of the suction tube will cease to operate, since they are geared with the gear

connection between the suction means and the drive axle.

An additional object of the invention is the provision of novel means for tilting the suction pipe, and furthermore to provide a vacuum street cleaning machine, which may be drawn by any suitable power.

It is the aim that this improved vacuum street cleaning machine may be propelled or drawn by any suitable truck or wagon, as the case may be. For instance, an ordinary motor truck or a wagon including a body adapted to receive the debris or collection of material to be transported to a dump or reduction plant is designed to be connected to the street cleaning machine. Furthermore, it is the aim that the body of the truck or wagon is designed to have pivotal movement in a horizontal plane so as to permit the vacuum street cleaning machine to make turns as the truck or wagon turns.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings, and claimed.

In the drawings:

Figure 1 is a view in side elevation of the improved vacuum street cleaning machine constructed in accordance with the invention.

Fig. 2 is a top plan view of the same.

Fig. 3 is a vertical sectional view on line 3—3 of Fig. 2 longitudinally through the machine.

Fig. 4 is a horizontal sectional view through the suction tube, showing the suction creating means.

Fig. 5 is a transverse vertical sectional view on line 5—5 of Fig. 1.

Referring more especially to the drawings, 1 designates a suitable frame, which may be any general construction or configuration and may be constructed of any suitable material. This frame is mounted upon forward and rear axles 2 and 3 provided with forward drive supporting and rear traction

drive wheels 4 and 5. The supporting axle 3 carries a frame 5^a, which supports a triangular shaped frame 6. A suitable saddle 7 is swivelly mounted upon the triangular shaped frame, and in turn supports a blower or suction pipe or tube 8. It will be noted that this suction tube or pipe is capable of tilting movements, and slightly to the rear of the fulcrum of the suction pipe, the 10 pipe is provided with laterally and rearwardly extending casings 9, provided with chambers 10. The outer walls of these casings 9 have openings 11 through which air is drawn and secured to the inner faces of 15 the outer walls of the casings are flaps 12, which are adapted to open to allow air to enter the chambers through the openings 11.

Journalized in bearings of the casings 9 are shafts 13, which carry revoluble fans 14. These fans as well as the casings 9 and the suction tube or pipe 8 may be constructed of any suitable material, preferably sheet metal. The blades of the fan 14 for the greater part of their lengths extend radially 25 from the hubs of the fans. However, the outer portions of the blades are curved as shown in the direction of rotation of the fan, and as the blades rotate air is drawn in through the opening 11 about the axis 30 of rotation of the fans. Owing to the blades being curved in the direction of rotation of the fans, this inrush of air is forced forwardly through the suction tube, thereby creating a vacuum in the rear part of the 35 tube. The lower ends of the shafts 13 are provided with beveled gears 15, which mesh with the beveled gears 16, which in turn are carried by a transverse shaft 17. This transverse shaft 17 is mounted in suitable bearings 40 of a depending frame 18, which is carried by the suction pipe or tube 8. Also mounted in bearings of the depending frame 18 are shafts 19 and 20 provided with meshing gears 21 and 22. The gear 21 meshes 45 with a gear 23, which is carried centrally upon the transverse shaft 17. Carried by the drive axle 3 of the rear supporting drive wheels is a spur gear 24, which meshes with the spur gear 22 when the suction pipe or 50 tube 8 is lowered. It will be seen that when the suction pipe or tube 8 is lowered motion will be transmitted from the rear drive axle 3 to the fan shafts 13 through the medium of the chain of gears, so as to create a suction 55 in the suction pipe 8.

The rear portion of the suction pipe or tube 8 terminates in an enlarged suction end 25 provided with diverging curved side walls 26. This suction end 25, when lowered in 60 position adjacent the pavement or the surface which is being cleaned, is supported upon the rollers or caster wheels 25^a. The supporting wheels or rollers hold the enlarged suction end in substantially close position to the surface which is being cleaned,

and journaled in bearings of the ends of this suction end is a shaft 27 and rotatable with the shaft 27 are the hubs 28 of the rotary brushes 29. Mounted upon the shaft 27 and arranged in a space between the adjacent ends of the hubs of the rotary brushes 70 is a sprocket 30 provided with a sprocket chain 31. The bristles of the rotary brushes are spirally arranged, the spirals extending from the adjacent ends of the brushes toward their outer ends, so that the refuse or dirt is swept toward the center, as the suction end of the suction pipe or tube travels over the surface which is being cleaned. The rotary brushes are mounted in a chamber 75 of the suction end of the suction tube or pipe, and the dirt or refuse as it is ruptured from the pavement is brushed or swept toward the rear wall 32. The dirt or refuse falls back upon the pavement or other surface which is being cleaned, and as the suction inlet 33 of the suction duct 34 of the suction tube passes over the surface, the dirt or refuse is sucked or drawn through the suction duct. The sprocket chain 31 passes 80 through a slot in the forward wall of the chamber in which the brushes rotate, and in turn passes over a sprocket 35 carried by the shaft 19 of the depending frame 18, so as to rotate the brushes in the direction 85 of the arrow *a*, so that the dirt or refuse may be brushed or swept toward the wall 32. The forward end of the suction tube or pipe 8 communicatively connects with a receptacle 36 carried upon the main frame 100 of the machine, by means of a slip joint as indicated at 37. This slip joint or connection with the receptacle 36 is afforded owing to the receptacle being stationary, and in view of the fact that it is necessary for the 105 suction tube 8 to be tilted, so as to move the gear connections of the rotating fans in and out of gear with the drive axle of the machine. The dirt or refuse when drawn into the suction tube deposits at its forward end of the tube into the receptacle 36. A tube 38 is carried upon the suction tube 8 and it also has a slip connection 39 similar to the connection 37 with the receptacle 36. This tube 38 extends rearwardly and has 110 communicative connections 40 with the rear portion of the suction tube or pipe 8, so as to return the air that is forced into the receptacle back to and through the suction tube 8. Where the tube 38 has a slip connection 115 40 with the receptacle, a gauze or other fabric covering 41 of several plies is provided, so as to filter the air as it is allowed to return through the tube 38, in other words to separate the dirt or refuse 120 from the air.

Mounted in bearings of the frame of the machine is a shaft 43 having a segmental rack plate 43^a rockable therewith, there being a lever 44 carried by the shaft and mov- 130

able with the segmental rack plate, whereby the plate may be rocked in one direction or the other. Mounted pivotally, at 45, on bearings of the frame of the machine is an oscillating bar 46. One end of this bar 46 has pivoted thereto links 47, which in turn are pivotally connected at 48 to the suction tube or pipe 8. The other end of the oscillating bar 46 carries a segmental rack plate 49, the teeth of which mesh with the teeth of the segmental rack plate 43^a. When the lever 44 is moved in the direction of the arrow *b*, the segmental rack plates 43^a and 49 coöperate, thereby causing the bar 46 to oscillate, which in turn will pull upon the links 47 and cause the suction tube or pipe 8 to tilt. When the suction pipe or tube 8 is tilted in this manner, the spur gear 22 will disengage from the spur gear 24 of the drive 20 axle 3 of the machine, thereby stopping the suction fans which are mounted in the chambers 10. When the suction fans are at rest, the rotary brushes also cease rotating, and furthermore, the suction end of the suction 25 tube is removed from close position to the pavement or the surface which is being cleaned. The rear supporting wheels 5 are driven owing to their engagement with the pavement. It is obvious that by this connection, the frame which supports the dirt receiving receptacle from the frame of the truck which carries the motor, may be connected to a wheel supported frame (not shown) but which may be drawn by draft 30 animals. In view of this, it is obvious that this improved vacuum street cleaning machine may be either driven by motor power or by draft animal power.

It will be noted that the vacuum street 40 cleaning machine is supported upon a two-wheeled sulky affair, the wheels 5 of which serve as drive wheels for operating the revoluble fan when the suction pipe or tube 8 is lowered, as in Fig. 1. When the suction 45 pipe or tube 8 is positioned as shown in Fig. 3, the gears 22 and 24 mesh, thereby transmitting motion from the wheels 5 to the axle and thence to the gearing carried by the suction pipe or tube, and then to the revoluble fans in the chambers 10. The rear 50 portion of the suction pipe or tube 8 is supported upon caster wheels 25^a. The revoluble brush is driven through a sprocket chain connection 31 with the gearing between the 55 axle 3 of the wheels 5 and the revoluble fans. As the street cleaning machine passes over the surface of the pavement, the dirt and debris is drawn through the suction pipe or tube and discharged into the receptacle 36. This receptacle or body of the truck may be constructed as shown, though not necessarily, for it is obvious that it may be otherwise constructed. For instance, it may be made collapsible. Furthermore, the 60 receptacle or body 36 is designed to be air-

tight and while the dirt or debris is deposited in the receptacle 36, the air percolates through a gauze or other fabric covering 41 and passes rearwardly through the tube 38, and thence into the chamber 40^a, which is 70 formed upon the rear part of the suction pipe or tube. The air in the chamber 40^a then passes in the suction pipe or tube 8 through the opening 40^b and is then drawn by the revoluble fans into the forward part 75 of the tube 8, and back into the receptacle, thereby causing a suction or vacuum in the lower rear portion of the vacuum pipe. It is the aim to prevent any escapement of air from the receptacle or body 36 excepting 80 through the gauze or fabric covering 41, as explained above.

In order that the suction tube or pipe 8 may tilt, so as to disengage the sucking end of the tube from the pavement, the forward 85 end of the tube is provided with an airtight slip joint with the dirt receptacle. By this construction, the debris or dirt is allowed to enter the receptacle, and when it is desired to disengage the gearing of the fans 90 from the operating means, the tube may be very easily tilted, which causes a disengagement of the gears 22 and 24 and when this occurs the fans will cease rotating.

The drive wheels 5 have ratchet connections with the axle 3, so that the drive wheels may be properly rotated, and facilitate the turning of the apparatus. The ratchet connections comprise the pivoted spring tensioned paws 5^a which coöperate 100 with the ratchet teeth of the collars 5^b. Suitable casings 5^c are carried by the hubs of the drive wheels 5 so as to protect the ratchet connections. The drive wheels also have ball bearings 5^d. The axle 3 also operates upon ball bearings 3^e.

The invention having been set forth, what is claimed as new and useful is:

1. In a vacuum street cleaning machine, the combination with a frame provided with a dirt receiving receptacle, of supporting wheels, for said frame, a suction tube tiltably mounted upon the frame and having a slip joint with the receptacle, suction creating means carried by the tube, the rear part of the tube having a suction end, gear connections between the suction creating means and the rear supporting wheels, and means for tilting the suction tube to move the gear connections out of gear with the shaft of the drive wheels.

2. In a vacuum street cleaning machine, the combination with a frame having rear supporting wheels and provided with a dirt receiving receptacle, of a suction tube tiltably mounted upon the frame and having at its forward end a loose connection with said receptacle, the rear portion of the suction tube terminating in a suction end; suction creating means carried by the tube and pro- 130

vided with gear connections with the axle of the wheels, and means connecting the frame and the tube adapted to be actuated for tilting the tube to move the gear connections out of engagement with the axle of the wheels.

3. In a vacuum street cleaning machine, the combination with a frame having rear supporting wheels and provided with a dirt receiving receptacle, of a suction tube tiltably mounted upon the frame and including suction creating means, gear connections between said suction creating means and the axle of the wheels, the rear portion of the suction tube terminating in a suction end provided with a suction mouth, rotary brushes carried by the suction end and having operative connections with the gear connections of the suction creating means, and means connecting the suction tube and the frame and adapted to be manipulated for tilting the suction tube to move the gear connections out of gear with the axle of the wheels.

25 4. In a vacuum street cleaning machine, the combination with a frame having rear supporting wheels and provided with refuse receiving receptacle, of a suction tube tiltably mounted upon the frame and including a suction creating means, gear connections between said suction creating means and the axle of said wheels, the rear portion of the suction tube terminating in a suction end provided with a suction mouth, rotary brushes carried by the suction end and having operative connections with the gear connections of the suction creating means, a rock shaft mounted in bearings of the frame and having a segmental gear, a second shaft in bearings of said frame, a segmental gear on the second shaft and meshing with the first segmental gear and having a link connection with the forward end of the suction tube, and means for operating the rock shaft, whereby the forward end of the suction tube may be moved downwardly out of registration with the receptacle.

5. In a vacuum street cleaning machine, a frame having rear supporting wheels and provided with a refuse receiving receptacle, a suction tube tiltably mounted on the frame and provided with a slipping communicative connection with said receptacle, suction

creating means in the tube and having gear connections with the axle of the wheels, a chamber carried by the tube rearwardly of the suction creating means and also having a slipping communicative connection with said receptacle, the rear portion of the suction tube terminating in a suction mouth, and means carried by the frame manually actuated and connected to the forward end of the suction tube for severing the communicative connections between the forward end of the suction tube and the receptacle. 65

6. In a vacuum street cleaning machine, a frame, rear supporting wheels therefor, a refuse receiving receptacle on said frame, a suction tube tiltably mounted upon the frame and having at its forward end a slipping communicative connection with the receptacle, suction creating means in said tube operatively connecting with the axle of the supporting wheels, an air receiving chamber carried by the tube at the rear of the suction creating means, a pipe connected to said chamber and having a slipping communicative connection with the receptacle, and means mounted on the frame and connected to the tube for tilting the same for severing 80 the communicative connection between the receptacle and the tube and pipe.

7. In a vacuum street cleaning machine, a frame, rear supporting wheels therefor, a refuse receiving receptacle on said frame, a suction tube tiltably mounted upon the frame and having at its forward end a slipping communicative connection with the receptacle, suction creating means in said tube operatively connecting with the axle of the supporting wheels, an air receiving chamber carried by the tube at the rear of the suction creating means, a pipe connected to said chamber and having a slipping communicative connection with the receptacle, and means mounted on the frame and connected to the tube for tilting the same for severing the communicative connection between the receptacle and the tube and pipe, said tube when tilted causing a disconnection of the operative connections with the axles of the wheels, thereby stopping the operation of the suction creating means. 100

In testimony whereof I hereunto affix my signature.

PATRICK J. DUNN.
